UNITED STATES PATENT OFFICE.

FRANK PARDEE, JR., OF HAZLETON, PENNSYLVANIA, ASSIGNOR TO ANTHRACITE SEPARATOR COMPANY, OF HAZLETON, PENNSYLVANIA.

SPIRAL SEPARATOR.

Application filed July 28, 1923. Serial No. 654,308.

To all whom it may concern:

Be it known that I, FRANK PARDEE, Jr., a citizen of the United States, and a resident of Hazleton, Pennsylvania, have invented 5 certain new and useful Improvements in Spiral Separators, of which the following is a specification.

This invention relates to improvements in the construction of adjustable spiral 10 separators.

Spiral separators are commonly used for separating coal from slate and other impurities which are frequently mined in greater or lesser percentage with the coal. Such 15 separators depend upon friction and centrifugal force to separate the coal from the slate. It has heretofore been proposed to build a separator made of sections some of which are comparatively rough and some 20 comparatively smooth and certain of these sections have been adjustably mounted so that the frictional area of the separator runway can be varied. In one form of separator heretofore used the runway has been built 25 up of a series of segmental plates having friction pads secured thereto and pivoted plates have been secured to the runway adapted to be swung so as to cover or uncover the friction pads in order to vary the 30 frictional area of the runway. In such prior constructions the pivoted plate for covering or uncovering the friction surface has been mounted so as to move through a cut or slit formed in one of the segmental plates of the 35 separator. An example of such prior constructions is shown in the patent of John H. Becker No. 1,270,365 dated June 25, 1918. My invention relates to the type of separator 40 therein shown and aims to provide various structural improvements as hereinafter set forth in detail.

An embodiment of the invention is illustrated in the accompanying drawings in which; Fig. 1 is a side elevation of the upper 45 portion of the separator. Fig. 2 is an enlarged side view showing a friction jacket in its exposed position. Fig. 3 is a similar view showing the friction jacket retracted beneath one of the plates on the separator runway. Figs. 4 and 5 are plan views illustrating respectively the friction jacket in 50 its exposed and retracted positions. Fig. 6 is a fragmentary vertical section on line 6-6 of Fig. 4.

Fig. 7 is a detail view on line 7-7 of 55 Fig. 2.

Fig. 8 is a detail view showing a modification.

The separator illustrated has two runways indicated at 10 and 12 over which the material to be separated travels, such material being fed to the upper end of the runways through suitable feed chutes 14 and 16. Part of the pure coal traveling along the outer zone of the runways 10 and 12 falls 60 off the outer edges thereof and is caught in the conveyor spiral 18 which delivers it to a suitable discharge bin, not shown. The runways 10 and 12 are of substantially the same construction and a detailed description of one will suffice for both. 70

A central supporting post 20 carries a number of spirally arranged rods 22 which extend outwardly and upwardly in a substantially radial direction. These rods support the plates which make up each runway. The conveyor thread 18 is supported in a similar manner by a plurality of rods 24 as shown in Fig. 1. 75

The separator runways 10 and 12 each 80 comprise a series of substantially triangular shaped segmental plates 26 which overlap one another as best shown in Figs. 2 and 3, the lower portion 28 of each plate extending beyond the upper portion 30 of the adjacent plate. The lower portion of each plate is offset as shown at 32 in Fig. 6 so as to provide an opening 34 through which a jacket adapted to vary the frictional area of the runway can be moved. The surface 90 of the runway can be roughened and a jacket moved out from said roughened surface to cover the same, or as illustrated in the form of the invention shown, a friction jacket 36 can be moved to the position shown in Figs. 95 2 and 4 where the greater part of its friction surface is exposed. This friction jacket can be retracted as shown in Figs. 3 and 5 so as to present practically none of its surface to the material traveling on the runway. By positioning the jacket in various intermediate positions it is apparent that a wide range of frictional adjustment for the runway may be secured. In separators of 100 this type heretofore used the movable sections have been pivoted to some part of the runway and this has resulted in giving only 105 a comparatively small adjustment. In the

improved design shown herein practically the entire surface of the friction jacket can be exposed when desired or said jacket can be entirely withdrawn so as to entirely 5 eliminate the frictional effect thereof thereby giving a wider range of adjustment than prior constructions.

The adjustable jacket 36 is arranged to be moved in an arcuate path which is substantially concentric with the axis of the central supporting post 20 of the separator. With jackets pivoted to the runway as in former constructions the pivots and the space between the movable and fixed jackets 15 frequently became clogged with a dust and small particles and frequently jammed so tight as to interfere with the adjustment.

In the improved construction herein shown there are no pivotal joints and the 20 adjustable jacket 36 is very loosely mounted and passes freely through the opening 34 between the overlapping portions of the adjacent segmental plates. At its rear end each jacket 36 is formed with a downwardly 25 extending flange 38 which is secured by rivets 40 to a flange 42 formed on a member 44 which member at its rear is provided with a pair of downwardly extending ears 46 which straddle the spiral bar 48 which is 30 mounted for substantially circular movement in guides 50 secured to the radial rods 22. The spiral bar 48 can be moved by any suitable means for example by a lever 52 shown in Fig. 1 which may be pivoted to any 35 suitable support and connected by a link or pin and slot connection with the bar 48. When the bar 48 is moved it is arranged to simultaneously adjust or position the several 40 of the movable jackets 36 arranged along the spiral runway. To this end the bar is provided with means for transmitting its movement to the jackets 36 as shown in Figs. 2 and 3. A sleeve 52 which passes through 45 an opening 54 in the member 44 is secured to the bar 48 by means of a bolt 56 and a nut 58. The sleeve 52 passes quite freely through the opening 54 so that the jacket 36 may move toward and from the bar 48 in a substantially vertical direction or stated 50 more accurately it can move to and from the bar in a direction at right angles to the direction of the movement of the jacket 36.

Because of the overlapping arrangement 55 of the segmental plates 26 forming the runway it will be noticed that the distance between the lower end of one of the plates and the bar 48 (as indicated at *a* in Fig. 2) is greater than the distance between the upper end of the plate 26 and the bar (as indicated 60 at *b*). In other words the space between the bar and the underside of a given segmental plate converges. If the movable jacket 36 were rigidly secured to the bar, when the latter was pulled back the jacket would be 65 jammed between the plate and the bar.

This jamming is avoided by the slip joint illustrated it being apparent that when the jacket is pulled back from the position shown in Fig. 2 to that shown in Fig. 3, the sleeve 52 merely slips through the opening 54 and the rear end of the member 44 drops down upon the bar and finds its own seat, the forward end of the jacket 36 of course being supported by the portion 30 of the segmental plate 26. This arrangement 70 permits the circular movement of the bar 48 to be readily imparted to the several movable plates 36 located at different portions along the runway without undue labor. The guides 50 for the bar 48 as shown are 75 secured by bolts 60 to the radial rods 22. Each of these guides comprises a substantially U-shaped bracket 62 having anti-friction rollers 64 housed therein on opposite sides of the bar 48 as clearly shown in Fig. 6. 80 The several guides 50 are located substantially the same radial distance from the vertical axis of the separator therefore it will be understood that when the bar is moved it 85 travels in a substantially circular path concentric with the axis of the separator. 90

From the foregoing description it is clear that the several movable members or friction jackets 36 are mounted in such a way that they can be moved together with relation to the runway and that their connection with the operating bar is in the nature of a slip joint which will not wedge or become jammed. It is also clear that in the design 95 shown it is unnecessary to cut openings or slits in the fixed segmental plates on the runway for the passage of the movable plates 36 nor is it necessary to provide special cover plates beneath which the friction pads are withdrawn. In the drawings 100 I have shown the sleeve 52 secured to the ring and passing freely through an opening in the member 44 and have shown the ears 46 straddling the bar 49 so that the plate or friction jacket 36 is prevented from moving 105 laterally with respect to the bar 48 but is compelled to partake of the substantially circular or spiral movement of the bar. It is to be understood that I am not limited to this exact arrangement as it is clear that the 110 stud could be fixedly secured to the member 44 and pass freely through an opening in the bar 48 to secure the same action and that instead of forming ears 46 on the member 44 I could provide projections on the ring 115 48 to straddle a portion of the member 44. 120

In the foregoing figures a member 44 is shown of substantially triangular contour in plan, the flange 42 extending transversely for practically the full width of the flange 125 38 on the plate 36 and the ears 46 being bent downwardly at the extreme end of said member 44.

As an alternative for the member 44 shown in Figs. 1 to 7 I may use the member 44^a such 130

as shown in Fig. 8. This is of much less width than plate 36 and is formed of a simple rectangular piece with the corners at one end bent downwardly so as to form the ears 46^a. This member is formed with the opening 54 for the passage of the stud 52 and is secured to the member 36 by rivets 40 passing through a flange 42^a and the flange 38 of the movable member. This member 44^a requires very little cutting as it can be made from the rectangular plate stock, the ears being readily bent by any suitable dies or it can be easily bent to shape by hand tools.

15 Though I have described with great particularity a specific embodiment of the invention herein shown it is not to be construed that I am limited thereto as various changes may be made and mechanical equivalents substituted without departing from the invention as defined in the appended claims.

What I claim is:

1. In a spiral separator having movable jackets for varying the frictional area of the runway means for moving the jackets in an arc substantially concentric with the vertical axis of the runway.

2. In a spiral separator a runway formed of a series of segmental plates overlapping along their adjacent edges, said jackets having portions spaced apart where they overlap to form an open slit, and a movable jacket arranged to be moved through said slit in an arcuate path substantially concentric with the vertical axis of the runway.

3. In a spiral separator a runway formed of a series of segmental plates arranged to overlap one another in such manner as to provide openings or slits along the edges of said plates, a friction jacket movable through one of said slits, a spiral bar for moving said jacket, and means for connecting the bar with said jacket so that they move together in the same arcuate path.

4. In a spiral separator a runway formed of a series of segmental plates arranged to overlap one another in such manner as to provide openings or slits along the edges of said plates, a friction jacket movable

through one of said slits, a spiral bar for moving said jacket, and connecting means whereby the bar and the jacket are movable together in a substantially arcuate path and yet are free to move relatively to one another in a direction substantially perpendicular to their plane of movement.

5. In a spiral separator a runway comprising a series of segmental plates overlapping along their radial edges and having portions offset at such edges to provide a space between the overlapped plates, a friction jacket movable through said space and arranged to be moved from under one segmental plate over the adjacent segmental plate, a spiral bar guided below the runway for movement in a substantially circular path, and a slip joint between said bar and said friction jacket whereby the circular movement of the bar is transmitted to the jacket yet the two are permitted to move relatively to one another so as to prevent the jacket being jammed when it is withdrawn below one of said segmental plates.

6. In a spiral separator having movable jackets for varying the frictional area of the runway, a spiral bar for moving said jackets in an arcuate path substantially concentric with the vertical axis of the runway and means connecting the bar and the jackets arranged to transmit the movement of the bar to said jackets and yet permit the jackets to move toward and from the bar so as to prevent jamming the jackets against the underside of the segmental plates when said jackets are withdrawn.

7. In a spiral separator having movable jackets for varying the frictional area of the runway, a spiral bar for moving said jackets in an arcuate path substantially concentric with the vertical axis of the runway, said jacket having a member secured thereto which is provided with depending ears adapted to engage opposite sides of the bar and a stud secured to the bar and loosely engaging said member.

In witness whereof, I have hereunto signed my name.

FRANK PARDEE, JR.
